COMBINATION DREDGING, DRILLING, AND
PILE-DRIVING EQUIPMENTJoseph O. Grenier, Vancouver, British Columbia,
Canada

Application July 29, 1937, Serial No. 156,394

8 Claims. (Cl. 37—71)

This invention relates to improvements in equipment for carrying out sub-aquatic work such as digging, dredging, blasting, pile-driving and setting operations by use of a unitary machine adapted for carrying out such a variety of operations either afloat or ashore.

My invention, in one form, is an improvement on the direct line method of lifting and disposing of material in so far as it takes up smaller working space and can be worked in a pocket or small clearance, removing all the material required without the possibility of losing any of it in the operation.

It is also an improvement on the usual type of ladder bucket dredge which operates the bucket at an angle and thereby only partially fills the bucket and so disturbs the material that much is washed away that cannot be recovered.

It is also an improvement on the sand pump dredger because it recovers everything required down to bed-rock, a characteristic not obtainable in a sand pump due to the higher specific gravity of certain metals which will wash away rather than be raised by the water and silt.

My invention is also an improvement on the dipper arm type, as this form of dredger is limited by the length of arm employed. This form of dredge also cannot be successfully employed in swift-flowing waters, for which my invention is particularly adaptable.

My invention has been designed so as to provide extreme portability as it can be assembled and dismantled at any point and transported to any other location for reassembly.

My invention is particularly convenient to use as marine equipment when mounted on floats or pontoons, as the equipment may be readily held in position by the mooring lines of the pontoons or floats and no further anchorage or haulbacks are required, such as are necessary in drag-line operations.

Nothing more is required for my invention than a single mooring line as the leads and spud, when lowered, will hold the pontoon or float in any position during operations.

My invention has for one of its principal objects the providing of an efficient dredging machine capable of carrying out operations in a new and original manner.

Another particular object of my invention is to provide equipment capable of carrying out sub-aquatic digging operations such as may be required when sinking and setting caissons and such like work.

Another important object of my invention has

been to provide equipment capable of carrying out sub-aquatic drilling operations in addition to being capable of digging and dredging operations.

Still another particular object of my invention has been to provide equipment capable of carrying out pile-driving and pile-setting operations in addition to being capable of effecting other important operations.

A further object of my invention has been to provide equipment capable of carrying out sub-aquatic blasting operations for the removal of under-water obstructions.

Still further objects of my invention have been to provide mobile equipment capable of being mounted upon pontoons, wharves, jetties, floats or rafts, and suitable for carrying out every variety of sub-aquatic operations that may be called for, by the mere interchange of auxiliary equipment.

With these and other objects in view, I have devised and invented the equipment which comprises the subject matter of this application and which is more fully described in detail in the following specification and illustrated in the accompanying drawings forming part of this application, and in which:

Figure 1 is a plan view of equipment and diagrammatically illustrates the position of the superstructure and framework with braces and shows position of guides and leads therein, also position of the various power drums mounted on deck, also the position of rear spud and framework.

Figure 2 is a general elevational view of equipment and shows position of guides, leads and operating cables mounted therein, also illustrates the rear spud member and operating cables thereto, also shows front anchor member lowered and cables woven therein and attached to drag member. Illustration purely diagrammatic.

Figure 3 is a general elevational view of equipment showing leads and bucket lowered, and illustrates dredging bucket in reversed position and at the commencement of the digging stroke, and shows rear spud lowered to hold equipment in position.

Figure 4 is another side elevation of equipment showing how leads may be angularly inclined in the pivoted guide members by the various cables to enable operations to be effected.

Figure 5 is a front end elevation of equipment mounted upon a floating foundation such as pontoons or the like, and illustrates the guides and braces thereto and the leads mounted in the

guides partially lowered below the foundation line of the equipment.

Figure 6 is a perspective view of hammer-head and dredging bucket pivoted thereto and shows 5 portion of operating cable of the dredging bucket attached thereto.

Figure 7 is an elevational view of one of the 10 guide blocks for mounting in the leads when drilling or pile-driving operations are to be effected.

Figure 8 is a top plan view of one of the guide members, showing how same is mounted in leads and shows central aperture which may be adapted for holding piles, drill rods or casings, and illustrates in cross section a view of the leads mounted 15 in the guide members.

In these drawings like numerals indicate like parts and the numeral 1 indicates a floating structure upon which is mounted a superstructure 2 in the framework of which is incorporated 20 a pair of guides 3 pivotally mounted at 4.

Within the guides 3 is mounted a pair of leads 5 which are slideable and adjustable therein by the cables 6 and 6X. The guides 3 are built upon opposite sides of a longitudinal opening 1 formed 25 in the front and center of the floating structure 1 which terminates in a tunnel through the after-part of the structure; firstly to provide a suitable location for the guides 3 and leads 5 to operate in, and secondly to facilitate the maneuvering 30 of the floating structure 1 in carrying out operations.

The superstructure 2 and framework have, preferably, for their foundation members long stringers or skids 8 with suitable side brace members 9, illustrated in Figure 1, so that, if the equipment is required to work upon a wharf or jetty, it can be removed from its floating foundation and be mounted to work off a stationary one.

The superstructure 2 and framework are preferably constructed in units or sections, there being two main side sections of framework secured together with suitable cross braces 10 at the top and rear of the guides 3.

The foundation stringers of the superstructure 45 2 are mounted adjacently and parallel with the sides of the longitudinal opening 1 of the floating structure 1 and are secured in any suitable manner to the deck thereof.

The slideable leads 5 are built up to length to 50 make them suitable for the work in hand and may be of any length desired and are intended and adapted for lowering below the foundation line of the superstructure 2 and being forced into the underwater surface to relieve the floating structure 1 of strain during the time that operations of a sub-aquatic nature are being effected.

The leads 5 mounted in the guides 3 are adjustable therein by a new and novel arrangement of the cables 6 and 6X. Mounted upon the 60 fore and aft sides of the leads 5, and adjacent the top and bottom thereof, are the sheaves 11, 11A, 11B and 11C. Built into the sides of the leads proper, and adjacent the top and bottom, are the sheaves 12, 12A and 12B.

65 Mounted on the deck or floor of the equipment a little aft of the guides 3 are a number of loose guide sheaves 50 over which all of the cables from the head of the leads are led to the various winding drums 26 on deck.

70 The manipulation of the leads 5 is entirely controlled by the cables 6 and 6X for effecting the raising and lowering of the leads or maintaining them in a vertical or angular position.

One end of the cables 6 is secured at the corners 75 28 of the framework and passes upwards

around the sheaves 11 downwards to the sheaves 29 thence upwards around the sheaves 12 mounted in each side of the leads 5 thence downwards to the sheaves 30 and upwards to the sheaves 11A mounted at the top and upon the rear side of the leads 5 thence downwards to the guide sheaves 50 from which the cables are led to one of the winding drums 26.

One end of the cables 6X is also attached to the corners 28 of the framework and passes 10 downwards to the sheaves 11C thence upwards and around the sheaves 31 thence downwards and under the sheaves 12A mounted in each side of the leads 5 adjacent the bottom thereof, thence upwards and over the sheaves 32 thence downwards and around the sheaves 11B, then upwards and over the guide sheaves 50 to be led to the winding drums 26.

From the above description of the weaving of the cables 6 and 6X, and the positioning of the 20 various dead ends and the sheaves, it will be apparent that the leads 5 may be lowered, raised or inclined by the manipulation of the various power drums 26 upon some of which the cables 6 and 6X are wound.

Also it will be apparent that the cables 6 and 6X act as fore and aft stays to the leads 5 when in the raised position. Also it is quite apparent that the leads 5 may be lowered and forced with enormous pressure upon the bottom over which 30 the equipment is working by slackening off of the cables 6X and tightening up of the cables 6.

The sheave 12B, mounted higher up and above the sheave 12A in the sides of the leads 5, is merely an extra one to permit of the leads 5 35 being lowered more deeply into an excavation than is possible when the cables are woven through the bottom sheave 12A.

Mounted in the center and at the top of the 40 leads 5 are the two sheaves 13 and 13C, over which run the cables 14 and 14D. To one end of the cable 14D is attached the drop hammer-head 15 having a lug 16 formed at each of the lower corners thereof.

The hammer-head is mounted in the slideway of the leads 5 and is adapted for driving piles or drill rods or performing other duties as the work demands.

In the center of the front face of the hammer-head and at the top thereof is mounted a sheave wheel 19, the purpose of which will be detailed a little later. The sheave wheel 19 is covered by a pivoted hood 20 for the purpose of protecting the bearings and wheel 19.

55 Adapted for connection to the lugs 16 of the drop hammer 15 is a dredging bucket 17 having lugs formed at the bottom thereof registering with the lugs 16 of the hammer-head to which they are pivotally connected by the pivot rod 18.

The bucket 17 is preferably of tapering cross section and has sharply tapered sides 21 forming the top or mouth of the bucket, to the lower edge of which are mounted the cutting teeth 22.

60 Adjacent the top of the bucket is mounted a pivoted bail 23 to the center of which is secured the pivoted sheave block 24 by the pin 25.

One end of the cable 14 is attached to the pin 25 and is passed around the sheave wheel 19 at 70 the top of the hammer-head 15, thence through the sheave block 24 attached upon the bail 23 of the bucket, after which it passes upwards and over the sheave 13 mounted at the top of the leads 5, thence down under one of the guide 75

sheaves 50 to one of the power drums 26 on the deck or floor of the equipment.

The power drums 26 are suitably housed in a power house 51 built on deck aft of the mounting of the guide sheaves 50 and the operation and manipulation of all of the power cables of the equipment are centered in the power drums 26.

The cable 14 is the operative cable only of the bucket 17 to cause the latter to function and 10 is not the lifting cable as that function is carried out by the cable 14D, one end of which is attached to the eye bolt 27 of the drop hammer-head 15, and the opposite end, after passing over the sheave 13C mounted in the head or top of the 15 leads 5, is mounted upon one of the power drums 26.

When dredging or excavating operations are to be carried out, the cable 14 is slackened completely off to permit the bucket 17 to descend in an upper side down or reversed position, as illustrated in 20 Figure 3.

After the bucket 17 is in reversed position, the cable 14D is then slackened off and the hammer-head 15 and bucket 17 are lowered together.

A powerful, penetrating effect is exerted by the 25 teeth 22 and lip of the bucket, when on the bottom, to cause it to dig by reason of the combined weight of the bucket 17 and the hammer-head 15.

As the hammer-head 15 is lowered in the leads 30 5, the weight of the hammer forces downwardly the bottom or inner end of the bucket and causes the teeth 22 and lip of the bucket to travel outwardly in the form of an arc while digging.

After the hammer-head 15 has reached the 35 bottom of the leads, the cable 14 is then tightened and causes the cutting edge of the bucket 17 to describe an upward arc as the bucket is brought to a vertical position full of debris, after which the bucket is hoisted by winding up of the cables 40 14 and 14D.

When pile-driving operations are to be effected, the bucket 17 is removed completely off the hammer-head 15 and suitable guide blocks 33 are mounted in the leads 5 whereby piles may be held and guided therein during driving operations.

Some of the guide blocks 33 may be arranged 45 to hold drill rods for drilling operations or may be arranged to hold casings while drilling operations can be carried on within the casings.

It is quite possible, with the equipment I have 50 invented, to effect operations impossible with ordinary equipment, as, for instance, it is quite possible to perform underwater pile-driving operations with exactitude of positioning of the piles, as, by reason of being able to raise the leads, it is quite possible to position a pile in the guide blocks 33 mounted in the leads, then lower the leads and pile together to the bottom and, if the head of the pile is submerged, it is quite possible 55 to put in an extension drive member suitably mounted in guide blocks above the head of the pile, and drive the pile by dropping the hammer-head 15 upon the extension drive member.

Adjacent the bottom of the leads 5 and below 60 the sheave 11C are mounted, upon the front of the leads, eye plates 34 adapted for mounting therein the shank end of an anchor member 35, the outer end of which is connected to a cable 36 running to hand winches 37 mounted on deck 65 and upon each side of the longitudinal opening 7. The hand winches 37 are used for lifting and raising the outer ends of the anchor member 35.

Suitably mounted upon the outer end of the anchor shank are sheave wheels 38 adapted for weaving over the end of a drag cable 39, one end

of which is attached to the rear of a drag 40, the forward end of which is attached to another cable 41 which is woven over a sheave 42 mounted adjacent the end of a spud member 43 carried in a suitable framework 44 built at the rear end of the deck or floor of the equipment.

Both inner ends of the cables 39 and 41 are led upwards to the deck and over suitable guide sheaves to the power drums 26, by manipulation of which the drag member 40 is caused to function to effect dragging operations and remove boulders from the vicinity of the dredging bucket 17.

The spud member 43 is manipulated and controlled by a cable 45, one end of which is secured at 46 on deck and then is led upwardly to pass 10 over a sheave 47 thence downwardly and around the sheave 48 from which it passes upwardly and over sheave 49 and thence downwardly to the 15 deck and one of the power drums 26.

To the top of the spud member 43 is attached 20 another cable 52 which is led downwardly and around a suitable guide sheave to one of the power drums 26. The cable 52 is for the purpose of forcing the spud member downwardly into the underwater bottom and to load weight of the 25 equipment upon the spud to cause it to hold.

One of the principal characteristics of my invention is the ability to dig and excavate to great depths by reason of being able to lower the leads to any depth desired, which depth is only 30 limited by the length of the leads themselves, which latter may be built to meet any conditions encountered.

Extra sheaves, after the manner of 12, 12A and 12B, may be built into the sides of the leads 35 5 above the sheave 12B and below the sheave 12, if desired, to provide for an increased range of manipulation of the leads 5.

No attempt in this specification has been made to describe detailedly the whole range of operations that may be effected by the above described 40 equipment and accessories that may be used, but sufficient pertinent details have been given to show that my invention has a very large range of operations and that some of these operations can 45 not be performed by ordinary dredging equipment.

Having now described my invention and the general nature of same, what I claim and desire to be protected in, by Letters Patent, is:

1. In apparatus of the character described, power means, a superstructure having sheaves, cables and pivotally mounted guides therein adapted to be placed in vertical or angular positions by manipulation of said cables, leads adjustably and slidably mounted in said guides and being co-operatively engaged by said cables whereby said leads may be lowered in a vertical or angular position below the fundation line of said superstructure to act as spuds, a hammer-head 55 reciprocatably mounted in said leads, a dredging bucket pivotally connected to said hammer-head and adapted for digging and dredging purposes, cables connected to said hammer-head and dredging bucket and co-operatively connected to 60 said power means whereby on manipulation of said cables and power means the said hammer-head and dredging bucket are energized to effect digging and dredging operations.

2. In apparatus of the character described, 70 power means, a superstructure having sheaves, cables and pivotally mounted guides therein adapted to be placed in vertical or angular positions by manipulation of said cables, leads adjustably and slidably mounted in said guides 75

being co-operatively engaged by said cables whereby said leads may be lowered in a vertical or angular position below the foundation line of said superstructure to act as spuds, a hammer-head reciprocatably mounted in said leads, a dredging bucket pivotally connected to said hammer-head in such manner that after filling said bucket may be brought to a vertical position by cables connected thereto and be hoisted by cables connected to said hammer-head and co-operatively engaged by said power means whereby on manipulation of said cables and power means the said hammer-head and dredging bucket may be energized to effect digging and dredging operations and said bucket may be hoisted in a vertical position while retaining all the contents of digging within said bucket up to the point of dumping, and means to dump said bucket.

3. A dredging equipment, comprising, power means and a superstructure adapted for installation upon a floating equipment, guide members pivotally mounted in said superstructure, slideable leads mounted in said guide members and having means for vertical or angular adjustment within the pivoted guide members whereby said leads may be lowered vertically or angularly below the foundation line of said superstructure, a slideable head member mounted in said leads and having means for reciprocation therein, means for pivotally connecting a dredging bucket to said head member and means connected to said bucket and power means to cause said bucket to pivot upon said slideable head member and scoop up gravel and effect dredging operations when said slideable head member and pivoted dredging bucket are lowered in said leads to a river bed.

4. A dredging equipment, comprising, power means and a superstructure adapted for installation upon a floating equipment, guide members pivotally mounted in said superstructure, leads mounted in said pivotal guide members, sheave blocks built into the sides of said leads, two pairs of blocks being adjacent the bottom and one pair adjacent the top, sheave blocks mounted upon said superstructure and having cables secured and woven therethrough and through said sheave blocks which are built into the sides of said leads whereby the latter become slideable and adjustable in said pivoted guide members and may be lowered below the foundation line of said superstructure by manipulation of the power means of said dredging equipment to which one end of said cables is attached, a slideable head member mounted in said leads and having a dredging bucket pivotally mounted thereto and being connected by cables to said power means whereby dredging operations may be effected by manipulation of said cables and power means.

5. A dredging equipment, comprising, power means and a superstructure adapted for installation upon a floating equipment, pivotally mounted guide members in said superstructure, leads mounted slideably in said guide members and having means for vertical or angular adjustment, a slideable head member mounted in said leads and being reciprocatably mounted therein, cables from said power means for operating said head member, means for pivotally mounting a dredging bucket on said slideable head member, said dredging bucket having cables attached to it and to said power means and adapted for lowering in a reversed position whereby the digging edge of

said bucket is brought into contact with the gravels of a river bed and is caused to describe an arc and scoop up said gravels to effect dredging operations when said cables and power means are operated to a degree sufficient to bring said bucket to an upright position upon its pivotal mounting and be hoisted in said leads.

6. A dredging equipment, comprising, power means and a superstructure adapted for installation upon a floating equipment, said superstructure supporting a pair of pivotally mounted guides having means for slidably and adjustably mounting therein a pair of leads, said leads adapted for lowering below the foundation line of said superstructure, a slideable head member mounted in said leads, bearings formed at the lower corners of said head member, a head sheave block mounted at the top of said slideable head member, a dredging bucket having one end pivotally mounted in said bearings, a pivoted bail member mounted on said bucket, a bail sheave block mounted on said bail, a cable attached to said bail and woven through said head sheave block and bail sheave block and over a sheave block mounted at the top end of said slideable leads and down to said power means whereby suitable manipulation of said power means the said dredging bucket may be caused to operate and effect dredging operations.

7. In apparatus of the character described, a barge, a spud device mounted on one end of the barge, means to operate said spud device, a superstructure mounted on the other end of the barge, a pair of guides pivotally mounted on a horizontal axis on said superstructure, said guides having slideways, a pair of leads having slides to cooperate with said pivot guides, means uniting said leads to slide along said guides as a unit, means for operating said leads to serve as a front spud for the barge, a drop-head slidably mounted between and on said leads, means to slidably operate said drop-head, a dredging bucket pivotally mounted at its closed end on said drop-head to project with its open end downwardly from said drop-head to be forced into a river bed upon dropping said drop-head and means to swing the bucket on its pivot to an upright position and hold it so while elevating the load.

8. In apparatus of the character described, a barge, a spud device mounted on one end of the barge, means to operate said spud device, a superstructure mounted on the other end of the barge, a pair of guides pivotally mounted on a horizontal axis on said superstructure, said guides having slideways, a pair of leads having slides to cooperate with said pivot guides, means uniting said leads to slide along said guides as a unit, means for operating said leads to serve as a front spud for the barge, a drop-head slidably mounted between and on said leads, means to slidably operate said drop-head, a dredging bucket pivotally mounted at its closed end on said drop-head to project with its open end downwardly from said drop-head to be forced into a river bed upon dropping said drop-head and means to swing the bucket on its pivot to an upright position and hold it so while elevating the load, said bucket having cutting teeth, said bucket swinging means including a sheave on said drop-head, a bail on the bucket, a bail sheave on the bail and a cable secured to the bail and passed through said sheaves.

JOSEPH O. GRENIER.
